UNITED STATES PATENT OFFICE

2,584,039

BREAKUP BANK FOR COMPOSING ROOMS

Georg Muff, Berne, Switzerland, assignor to
Luscher, Leber & Co. A. G., Berne, Switzerland,
a joint-stock company

Application September 22, 1950, Serial No. 186,147
In Switzerland March 5, 1949

4 Claims. (Cl. 312—196)

1

This invention relates to labor-saving devices for the composing room of printing shops. It is particularly concerned with means for saving labor and money in the operation of breaking up dead type and sorting part of it for distribution back into the storage case, while discarding the remainder for re-casting.

It is an object of this invention to provide a break-up bank which saves a great amount of labor by enabling the break-up man to dispose of the dead matter and sort part of it for re-distribution in less time, with greater ease and with the least possible expense of energy of his own.

In order to attain this end, the break-up bank according to this invention comprises a combination of means including a work table forming the top of a knee-hole desk structure, galleys to the rear of, and partly arranged at a higher level than, said table, receptacles and galleys below said table accessible through openings in the table top, and a slideable receptacle, preferably mounted on wheels and reciprocable in the knee-hole space, to allow the break-up man to perform his work in sitting posture and with his legs temporarily stretched so as to avoid cramps.

The attached drawing illustrates, by way of example, an embodiment of the break-up bank according to the invention.

Fig. 1 is an elevational view,

Fig. 2 is a plan view,

Fig. 3 is a sectional view along the line III—III of Fig. 2,

Fig. 4 is a sectional view along the line IV—IV of Fig. 2.

The device shown in the drawing is a desk-like structure comprising two lateral frames 1, 1 housing three large drawers 29 arranged in superposition and filling about two thirds of the vertical frame space, five galleys 19 on top of each row of drawers arranged for sliding back and forth motion like the drawers 29, and a number of shorter and narrower drawers 18 on top of each row of galleys 19.

3 is the desk top serving as work table and 20 is the front wall of the bottomless middle section 32 of the desk which extends below the table top and connects the two lateral frames 1, 1 leaving free the knee-hole opening 33 in which a carriage 22 can be moved by means of grips 23 back and forth by the break-up man seated in front of the bank.

The bottom 24 of the carriage is inclined and the matter thrown into the chute 27 closed by a trap 28 hinged in an opening of the top drops onto the inclined bottom and can be evacuated

2

through the bottom opening of the carriage closed by a flap 25. A drawer 30 is provided in the middle front wall 20 below the top 3.

To the rear of the trap 28 closing the chute 27 is mounted a shelf 4 seated in an opening 34 of the table top 3, its rear wall 7 being curved concentrically to the break-up man's seat (not shown.) The top 8 of this shelf is inclined towards this seat and a row of segment-shaped containers 9 placed on this top and subdivided by ribs 11 into galleys is removably held in position. Underneath the shelf top 8 six curved rows of removable galleys 5 are arranged in superposition with their bottoms 6 (Fig. 3) inclined downwardly towards the rear.

As shown in Figs. 2 and 4, the desk top 3 is formed above the two drawer frames 1 with pairs of juxtaposed slots 12, 12 into which project the fixed top ends 16 of inclined slip galleys 13, which carry springs 14 bearing against movable members 15.

The galleys 13 are intended for the reception of leads, space, quads, etc., no matter of what length, as indicated at 17.

25 The drawers 18 which open from the front of upright 1 are for storing of brass or lead rules. These rules, which as is known print contrary to the space leads, are kept in the appropriate section of the drawer 18 according to length, thickness and impression.

30 The blocks are deposited in the specially supplied setting galleys 19.

The break-up man sitting in front of the device above described and in the center point of 35 the circle defined by the concave shelf 4, has before him within easy reach the work table, the chute 27 for the disposal of the machine type matter, the slots serving the slip galleys 13, the drawers 18, 19, 29, 30, the carriage 21 and the 40 many galleys 5 and 9 supported by the shelf structure. The arrangement of this shelf renders it easy for him to put all the many different types on the proper galley without ever rising from his seat. In view of this ease of working he 45 is able to go through the entire breaking-up operation in far less time and with greater accuracy, with considerable saving of energy, as compared with the break-up facilities hitherto available, and the printing shop saves money while the distribution of the type on the setting equipment of 50 the individual compositors is speeded up greatly.

The drawers 29 and 30 can be adjusted to meet varying requirements. For example drawer 29 in upright 1 can be used as reserve storage for 55 spacing.

I wish it to be understood that I do not desire to be limited to the details of construction and arrangement of the various parts of this device, as obvious modifications will occur to a person skilled in the art.

I claim:

1. A dead type break-up bank comprising a table having a top with a centrally disposed working area and apertures at each side of the central working area, a centrally disposed aperture in said table top located rearwardly of the working area for receiving Linotype matter, including trays in respective side apertures supported in an inclined position and slanting downwardly and rearwardly below said table top for storing rules, a chute carried below said centrally disposed aperture and extending downwardly therefrom intermediate said inclined trays.

2. A device as set forth in claim 1, including side support elements for said table having guides for a plurality of horizontally removable galleys, said guides extending rearwardly to points adjacent respective inclined trays and being progressively foreshortened accordingly so that the galleys carried in said guides in vertical juxtaposition may be of varying length to fit the length of respective guides.

3. A device as set forth in claim 1, including a cart disposed below said chute, the table hav-

ing an opening in a central area at the front to permit forward removal of said cart carrying discarded Linotype matter, said cart normally closing said opening.

4. A device as set forth in claim 1, including an additional aperture in said table top arcuately shaped and disposed rearwardly of said chute aperture, a vertically disposed shelf structure set in said aperture with the base thereof below said table top, including shelf elements disposed in downwardly and rearwardly slanting array and a row of receptacles slidably carried by each of said shelf elements for receiving hand type matter, the receptacles in the lowermost row having a sufficient length to protrude above the surface level of said table, the protruding portions being open to provide access to said receptacles.

GEORG MUFF.
